FLUORESCENT LIGHTING FIXTURE

Clifford Brooks Stevens, Milwaukee, Wis., assignor to
McGraw-Edison Company, a corporation of Delaware

Application September 28, 1956, Serial No. 43,122

Term of patent 14 years

(Cl. D48—19)

FIG. 1.

FIG. 2.

FIG. 3.

Fig. 1 is a top plan view of a fluorescent lighting fixture, showing my new design;

Fig. 2 is a side elevational view of a fluorescent lighting fixture.

Fig. 3 is an end view taken at either end of a fluorescent lighting fixture.

The light transmitting envelope portion of the fixture is continuous throughout its length, and width to provide a configuration substantially conforming to the contour of the marginal flanged portion at the junction of the envelope and the luminaire housing.

I claim:

The ornamental design for a fluorescent lighting fixture, as shown and described.
